Primary Examiner — Mark Goodwin(74) *Attorney, Agent, or Firm* — Yokoi & Co., U.S.A., Inc.; Toshiyuki Yokoi(57) **CLAIM**

The ornamental design for a fluid pressure cylinder, as shown and described.

DESCRIPTION

FIG. 1 shows a front view of a fluid pressure cylinder showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof; and,

FIG. 7 shows a top, front and left side perspective view thereof.

1 Claim, 4 Drawing SheetsFIG. 1

FIG. 2

FIG. 3

FIG. 4

FIG. 5

FIG. 6
